DANA BICKFORD, OF BOSTON, MASSACHUSETTS.

Letters Patent No. 80,121, dated July 21, 1868.

IMPROVEMENT IN KNITTING-MACHINE.

The Schedule referred to in these Letters Patent and making part of the same.

TO ALL WHOM IT MAY CONCERN:

Be it known that I, DANA BICKFORD, of the city of Boston, county of Suffolk, and State of Massachusetts, have invented certain Improvements in Knitting-Machines; and I do hereby declare that the following, taken in connection with the drawings which accompany and form part of this specification, is a description of my invention sufficient to enable those skilled in the art to practise it.

My improvements relate to circular-knitting machines, but particularly to that class of them in which a circular series of latch-needles reciprocate, while forming the stitch, in parallel grooves in a stationary needle-ring.

The object of my improvement is to render such machines capable of producing a greater variety of work than could heretofore be made upon them; to make them capable of being instantly reversed whilst in the act of knitting, and to any desired extent, so as to make both tubular goods or straight or flat web, or both connected, as in forming the various parts of a stocking or other shaped or "fashioned" article, to narrow and widen either the tubular fabric or the strip without change in the size of the needle-ring; to make on such circular machine a fabric with different-colored stripes running lengthwise of the tube or strip, or with such stripes themselves having different colors running crosswise of the same, so as to present in each stripe a cross-stripe or block; to make fancy tubular goods of different texture by employing at times all the needles of the series, and at other times a lesser number than the whole series, but by continuous revolution of the series in either one or the other direction; and, in addition, to make thereon ornamental fringe and cord, and to cover, by knitting, a core, whether the same be a cord, wire, flat spring, whip-handle, or other article.

The primary aim of these improvements is to cheapen and simplify, and also to enlarge the capacity of the machine, (which is made with a view to use in families, and by persons of but limited mechanical skill,) that the great and growing want of and demand for a family knitting-machine shall be met, it being well known that the so-called rotary family machines, as hitherto made, were limited to the mere knitting of a tubular goods corresponding in size to the diameter of the needle-cylinder, or were so complicated as to require a practical mechanic to run them and keep them in order.

My special improvements consist in such a construction of the cam-groove by which the needles are actuated, that the machine may be revolved in either direction and knit successfully, and in connection therewith, the employment of a cam or cams, which, by dove-tailing or otherwise, may be made to slide, for the purposes of adjustment; and in the employment of two such slides in two depressions of the groove or cam, both having such range of adjustment that they may insure a considerable variation in the traverse of the needles, to make looser or tighter work, and in a means for elevating or lowering the needle-cylinder, whereby also the work may be made tighter or looser.

Figure 1 represents a perspective view of a machine embodying my improvements.

Figure 2 is a cross-section of the same in the line xx of fig. 1.

A represents the frame or bed of the machine, to which is fixedly secured the needle-cylinder or ring B. The frame has a prolongation or extension, C, so that when the machine is clamped to the ledge of an ordinary table or piece of furniture, in the usual manner of hand-machines, this extension shall, by bearing upon a considerable surface of the table, afford a firm and steady purchase, so as to prevent that unsteadiness and constant shaking which, in driving the machines, have always attended them, as usually constructed, without such projecting surface.

D is the revolving ring or band, on which is mounted the thread-carrier E, in which is an eye for the thread, and a slit, F, leading to the eye, and admitting of ready threading or unthreading of the eye.

The ring D is caused to revolve by means of a toothed wheel, G, driven by a handle, H, the teeth of this wheel meshing into teeth on the ring.

Upon the inner face or periphery of ring D is a groove, I, to receive the butts of the needles. This groove is straight, except at that portion where it is intended to cause the needles to rise or fall, and at that portion it is formed substantially as shown at aa in fig. 2.

Adjustable pieces, K, dove-tailed or otherwise, so as to admit of being slidden and adjusted to various posi-

tions upwards or downwards, serve to vary the character and action of the cam-groove upon the needles, and to change their extent of traverse. The shorter the traverse the closer the stitch, and *vice versa*. Each of these sliding pieces is held firmly to its desired position by a thumb-screw, L, which, passing through an inclined slot, M, in the ring, serves to lift and lower and fasten the slide in its place. Each slide also is fitted in ways, which support or brace it on opposite sides, to prevent its getting out of true position. To each slide may be attached an index or pointer, which, passing through the slot, indicates upon a dial outside the ring the extent to which it has been moved, and consequently the character of the stitch to be made.

By having the cam-groove of the same form or shape on each side of its centre, and by having the two slide-pieces alike, and situated alike relatively to corresponding parts of the cam-groove, it is evident that in whichever direction the ring is caused to revolve, their action upon the needles will be unchanged, it being only necessary that each slide and its corresponding portion of the cam-groove shall be equidistant from a vertical line drawn through the eye of the thread-carrier, in order to insure the proper delivery of the thread to the needles, whether the ring revolves in one direction or the other. I sometimes dispense with the slide-pieces, and make the groove continuous throughout.

The needle-ring is grooved in the usual manner, to receive the needles and permit their rise and fall therein, but unlike such ring, as shown in my patent, No. 68,595, granted September 10, 1867, it has no groove around its periphery cutting the needle-grooves, and no hinged clasp fitting in such groove, and serving to aid in holding the needles in position, and also to hold the revolving ring to its place. In my present invention the revolving cam-ring is held down by clasps, N, or their equivalent, screwed to the bed-plate, and projecting far enough over the lower flange of said ring to prevent its rising, but yet loose enough not to retard its revolving movement. A loosening of these screws admits of a removal of the cam-ring, when desired.

In order to raise or lower at will the needle-cylinder relatively to the cam-cylinder, I make a screw-thread on the periphery of the needle-cylinder, at its lower end, or make use of some other equivalent means that will answer the same purpose, and I insert in the centre of the bottom of the frame a ring-nut, O, having a circular groove, e, on its periphery, and which is held in place by several projections, d, from the frame, which enter this groove. The ring-nut is thus free to be revolved. And to facilitate this, pins, P, serving as handles, project downwards from it. These parts act as follows: The needle-cylinder being first screwed into the nut to the proper distance to give it its true position for ordinary work, it may afterwards be raised or lowered to the extent desired by simply turning the ring-nut in the direction needed.

This feature is of great importance as a simple and efficient means for producing loose or tight work, even when my fixed cam-groove is used; but when used in the same machine, with the adjustable cam above described, it gives just so much additional range for that purpose beyond that due to the cams alone; in other words, the range is made equal to the range of both added together.

For some kinds of work so great a range of adjustment is not necessary, and I then omit the slides from the cams, and have no provision for the adjustment of the cam-groove, which is made continuous, and always the same; the raising and lowering of the cylinder alone serving of itself to give all the adjustment required.

I use two, three, or more bobbins, and a corresponding number of thread-guides, one for each; and I slit each of these from its eye outward, so that in the variety of work which my peculiar improvements enable me to make upon this simplified machine, each thread can be instantly removed from or replaced in its eye, or another colored thread, or two or more threads of the same or different colors placed therein. These bobbins are placed upon spindles which rise from that portion of the frame which projects over and rests upon the table, so that this projection serves the double purpose of aiding in the firm support of the machine, as before mentioned, and as a convenient but out-of-the-way stand for the bobbins.

Usually the spindles for the bobbins are placed upon a loose removable stand, and this is located anywhere the operator may find a place for it, but separate and apart from the machine. The disadvantages of this practice are, that the stand is liable to be upset, its position, and consequently the pull upon the thread, are variable, being dependent upon where and how the machine may be used, and neither the bobbins nor yarn-guides always occupy the same relative position to the operative parts of the machine. But by locating them upon and affixing them to the extension-piece C, and in permanent positions, the whole apparatus is rendered compact; the bobbin-spindles, bobbins, and their yarn-guides occupy no more area or table-room than is required for the machine itself; no extra movable stand or support is needed for them; and they are always in readiness, and always deliver the yarn in the same lines, and with the same amount of strain or pull.

This provision for and mode of throwing one thread out and another thread into a carrier, so as to make stripes around the work, and without the need of breaking off the thread, is of great importance.

Upon the machine, constructed as described, I am enabled not only to knit a fabric whose diameter will be equal to that of the ring of needles, (and which ring may be made of any size required,) but by knitting it looser, or with larger yarn, or both, and on all the needles, the diameter is considerably more than when knit tighter, or with finer yarn, or only upon a portion of the needles, more or less, at regular or irregular intervals, being omitted.

By knitting only partially around the ring, and then reversing the motion for the same distance, I am enabled to make, upon a circular machine, and with a single yarn, a straight strip or web having two finished selvedges.

By knitting such a strip in continuation of a leg of a stocking, (previously knitted upon the machine by the method above described of knitting a tube, and of swelling its size for a calf,) the heel-piece is formed; but as a double or thick heel as well as toe is generally needed in stockings, to meet the greater wear at those points, I double the work at these parts by simply doubling the thread. The toe is made by continuous narrowing, first of one half, and then of the other half of the toe-piece, and then joining these together by hand.

To make a continuous narrowing, say from the calf to the ankle of a stocking, legging, or garter, and at the same time give it a neat, novel, and attractive appearance, I take out a needle at each side of, say, any two or three needles, and then proceed and knit as many rows as desired, corresponding with the degree of narrowing required, and then take out two other needles, equally distant from those last removed, and so on continuously until the size has been reduced as much as the work demands. And the effect of this operation is to give longitudinal ridges in the work resembling ribbed knitting, the grooves between the ridges growing gradually shorter and shorter as they recede from the longest central one, which should be made to come in front of the stocking or legging.

I also knit upon this machine leggings with garter bottoms, an article never before, so far as I am aware, made upon a knitting-machine, and it, with other new products made on my machine, I shall seek protection for in other applications for Letters Patent.

In making mittens upon this machine, the process is mainly the same as in making a stocking.

To make a knitted cord, I use but two, or three, or more needles, and operate the machine as usual, each revolution of the ring and its yarn-carrier causing a delivery of the yarn to the barbs of the needles, and then carrying it across from the last to the first needle employed. If the needles used be very few, and the tension be sufficient, a tube will thus be formed, every stitch of which will seem precisely the same; but if the needles be more, and the tension less, the slack thread passed from the last to the first needle so employed will not be fully taken up, and this portion will present somewhat the appearance of a longitudinal rib in the cord, or a cord flat on one side. If many needles be used, and the machine revolved continuously, the unknitted thread from the last to the first of the needles employed will represent the chord of the arc formed by these needles, and the result will be a knitted puff.

If a few only of the needles at regular intervals be employed, as, for instance, at four equally distant points, and the machine be continuously revolved in one direction, the result will be a loosely-made tube, the fabricated or knitted part of which will be four equally distant parallel strips, held together by yarn unknitted. By cutting these apart lengthwise it becomes fringe.

By introducing a cord, or wire, or flat strip of metal, or other article, at a proper position, so that it may serve as a centre about which the slack thread may pass in going from the last to the first needle, as above mentioned in the making of cord, it becomes surrounded by and enveloped within the knitted tube, and this process affords a means for covering skirt-wires, whip-handles, window-curtain cord, &c., &c.

By knitting a straight piece with selvedge edges, or a tubular piece, for muffs, &c., and regularly (at such intervals, as may be desired,) detaining the yarn between the formation of any two stitches upon a pin, or otherwise, so as to form a loop of whatever length may be desired, or by knitting a course or part of a course, and then throwing the yarn over the same set of needles, and leaving a loose loop between such of the needles as may be preferred, and then knitting another course over these loops, the latter are secured in place, and the result is a rich tufted fabric, with long pile upon one surface of the knitted fabric, and formed of the same yarn which composes its base or foundation. By making very short loops, which may be done by carrying the thread over a wire, I make a goods closely resembling ordinary piled fabrics. If this pile be afterwards cut, it gives a velvety appearance. If the long tufts be cut, the fabric resembles a Turkey carpet in texture.

Of course in any of the varieties of work made on this machine, different-colored yarns may be thrown in or out, to suit the taste and to vary the pattern.

To make a fancy tippet, I knit regularly a tube as far as desired on all the needles, and then with another colored yarn knit much tighter or looser on the same number of needles, or knit only upon a lesser number, say upon every other needle; the result is an alternate close and loose mesh, the latter contracting naturally, the product being a new and attractive one.

In knitting a tubular piece, I have successfully surfaced one side of the tube with the long loop or tuft in the manner above described, and thus formed the outer surface for a knitted muff in imitation of fur. Instead of surfacing the knitted fabric with a tuft of the same material, I have successfully introduced, during the process of knitting, tufts of fur, wool, hair, or silk; which being held by the stitches, or being curled, make a still closer imitation of natural fur or skins.

In order to form longitudinal stripes in the knitted fabric, of a different color from the remainder, I proceed as follows: I allow a certain determined number of stitches to be formed of one colored yarn or thread, and then bringing into service a yarn of another color, knit as many stitches with it as will give the breadth of stripe desired, throwing the thread which is not in use off the inside of the work, and so continuing around the circle. The repetition of this for each course will produce the stripes. By continuing such stripes for a distance equal to the breadth of the stripe, and then changing the color of the thread for a corresponding distance in each stripe, a plaid goods will be produced.

It will be readily perceived that with the facilities in my machine for throwing threads in and out instantly, and without breaking them to do so, or without tying knots to resume the same thread, and by my simple means of reversing, and to any extent, and of driving the machine in either direction, the range of work it is capable of making is almost unlimited.

I sometimes knit into the goods strips of rubber or elastic cord, or form elastic cord by knitting a covering for strips of rubber. Strips of buckskin I also knit into socks or drawers, and long fibres, such as flocks, silk, &c., I knit into hats and bonnets.

1. I claim a longitudinally-grooved needle-cylinder, in combination with a rotary cylinder, having an endless cam-groove with two equal and similar bends, and two sliding cam-pieces, one for each bend, and each supported in side bearings or walls, so that proper adjustments may be made to tighten or loosen the stitches, and

yet which will permit the revolution of the machine in either direction, to knit either a tubular or straight fabric at will.

2. The combination with the needle-cylinder of a ring-nut and detents or projections *d*, for raising or lowering and sustaining in position the needle-cylinder relatively to the cam-cylinder, substantially as and for the purpose set forth.

3. Also I claim the combination, in the same machine, of devices substantially such as described, for varying the cam-groove, with devices substantially such as described for raising or lowering the needle-cylinder.

DANA BICKFORD.
